PUMP

Joseph B. Brennan, Bratenahl, Ohio

Application November 25, 1949, Serial No. 129,328

9 Claims. (Cl. 103—38)

1

The present invention relates generally as indicated to a pump and more particularly to an automatic, high-pressure, variable capacity pump.

One primary object of this invention is to provide a variable capacity pump which is of simple, fool-proof construction and which has a high mechanical and volumetric efficiency.

Another object of this invention is to provide a reciprocating piston pump in which a plurality of double-ended pistons are actuated through the intermediary of a tilted ring engaged with each piston, preferably in rolling engagement in the manner of gear teeth to achieve high efficiency.

Still another object is the provision of novel means for adjusting said tilted ring to automatically vary the capacity or displacement of the pump.

Other objects and advantages will become apparent as the following description proceeds.

To the accomplishment of the foregoing and related ends, said invention, then, comprises the features hereinafter fully described and particularly pointed out in the claims, the following description and the annexed drawings setting forth in detail certain illustrative embodiments of the invention, these being indicative, however, of but a few of the various ways in which the principle of the invention may be employed.

In said annexed drawings:

Fig. 1 is a top plan view of a preferred embodiment of this invention;

Fig. 2 is a cross-sectional view taken approximately along the line 2—2, Fig. 1;

Figs. 3 and 4 are transverse cross-sectional views taken respectively along the lines 3—3 and 4—4 of Fig. 2;

Fig. 5 is a plan view of one form of valve body employed in the present pump construction;

Fig. 6 is a cross-sectional view of said valve body taken substantially along the line 6—6, Fig. 5;

Fig. 7 is a fragmentary cross-sectional view of a modification employing a screw adjusted capacity-varying mechanism for the pump; and

Fig. 8 is a fragmentary cross-sectional view of a modification in the connection between a tilted ring and pistons actuated thereby.

Referring now to the drawings and first to the form of the invention illustrated in Figs. 1 through 6, there is provided a pump casing which comprises an intermediate tubular part 1 formed with one or more internal grooves 2 (herein six) milled or broached axially therethrough and with feet 3 for mounting the pump on a suitable support (not shown).

2

At the ends of said intermediate part 1 are opposed cylinder blocks 4, preferably identical as shown but facing in opposite directions, and each formed with cylinder bores 5 axially therethrough in alignment with the grooves 2 in said intermediate part. Fitted into each of the cylinder bores 5 in said cylinder blocks 4 are liners or bushings 6 of bearing material. The outer face of each cylinder block 4 is formed with radially inwardly extending grooves or recesses 7 intersected by the respective bores 5.

Adjacent one of the cylinder blocks 4 is a head 8 which is formed with a pair of annular chambers 9 and 10 and a pair of ports 11 and 12 respectively leading to such chambers. Said head is further formed with two series of openings 14 and 15 leading from the respective chambers 9 and 10 into circular recesses 16 formed on the inner face of said head, such circular recesses being opposed to the radially inwardly extending recesses 7 formed in the adjacent cylinder block 4.

Fitted into each circular recess 16 is a valving assembly which comprises a circular disk or valve body 17 non-rotatably fitted into the recess as by a dowel 18 thereon extending into a suitable opening in the bottom wall of the circular recess, said disk 17 being formed with openings 19 and 20 therethrough respectively registering with the openings 14 and 15 in said head 8 and with oblong recesses 21 on opposite sides extending generally tangentially. In each of such oblong recesses 21 is a thin valve plate 23 which functions as a check valve to open and close communication through said disk 17 in response to pressure or suction acting on opposite sides thereof and thereby controls the flow of fluid from and into the chambers 9 and 10 into and from the respective expandable chamber which is defined by the cylinder bore 5 and the piston reciprocable therein.

Said intermediate part 1, cylinder block 4, and head 8 are secured together as by the studs 24 and nuts 25, as shown.

The head 26 at the other end of the pump casting adjacent the other cylinder block 4 is similar to the head 8 and insofar as said heads 8 and 26 are the same, the same reference numerals have been used to indicate the various chambers, parts, openings, valving assemblies, etc. associated therewith.

Adjacent said head 26 is an actuator housing 27 which for purposes of illustration has been shown rotated 90° from its intended position with respect to the casing as a whole and which housing, as will be later described in detail, contains

the mechanism for effecting variation of the capacity of the pump. As shown, the intermediate casing part 1, cylinder block 4, head 26, and actuator housing 27 are secured together by any suitable means such as the studs 28 and nuts 29 shown.

Reciprocable in the cylinder bores 5 of said cylinder blocks 4 are the opposite ends of pistons 30 each of which has an intermediate section 31 of rectangular cross-section in sliding engagement in the grooves 2 formed in the intermediate casing part 1. Said intermediate section of each piston 30 is also formed with an inwardly opening recess 32, preferably similar in general form to the space between the teeth of a gear rack.

Journalled within the pump casing as by anti-friction bearings 34 carried in the opposed cylinder blocks and extending through the bushing 35 in head 8 is a drive shaft 36 having a splined end portion 37 through which the shaft may be driven.

Carried by said drive shaft 36 for rotation therewith and for tilting movement thereon is a ring assembly 38 comprising an inner ring 39, an anti-friction bearing 40, and an outer ring 41, said inner ring 39 having a specially formed bore 42 therein permitting tilting thereof with respect to the drive shaft about the axis of a pin 43 disposed transversely through said drive shaft with the opposite ends thereof extending into said inner ring, and said outer ring 41 being formed with a series of radial projections 45 of general form similar to spur gear teeth which tiltably fit into the inwardly directed recesses 32 formed in said pistons 30. Thus said projections 45 have a high efficiency rolling engagement with recesses 32 comparable with the engagement of the teeth of a spur gear and rack. Said inner ring 39 is further formed with a lateral ear portion 46 radially spaced from the axis of said pin 43.

The mechanism for tilting the above-described ring assembly 38 comprises a ring-like tilting member 47 non-rotatably but axially slidably carried by said shaft 36 and connected to said inner ring 39 as by means of a link 48 having its opposite ends pivotally connected to the outer portion of said member 47 and to the ear portion 46 of said inner ring.

As now apparent, axial movement of said member 47 will, through the link 48, effect desired tilting of the inner ring 39 and thus of the entire ring assembly 38 about the axis of pin 43. The axial sliding and non-rotary connection of said member 47 to the drive shaft is effected as by a transversely disposed pin 49 having its ends fitted into said member and extending through an axially elongated slot 50 formed in the drive shaft.

The operation of the structure thus far described is as follows.

Assuming that the ring assembly 38 is in a tilted position, as shown, the rotation of the drive shaft 36 will effect, through the pin 43, rotation of the ring assembly about the axis 51 to thereby effect reciprocation of each of the pistons 30 to draw fluid into one cylinder bore 5 at one end, through port 11, chamber 9, opening 14, and opening 19 and to discharge fluid from the other cylinder bore 5 at the opposite end through the opening 20, opening 15, and discharge chamber 10 and port 12. As apparent, the check valves are operative to alternately open and close

communication between cylinder bore 5 and chambers 9 and 10.

In the particular pump shown employing six double-ended pistons 30, fluid will be drawn into and discharged from twelve expanding chambers and twelve contracting chambers during each revolution of the drive shaft 36 and because of the uniform spacing of the pistons 30, the delivery at any instant is a constant whereby to eliminate pulsation. Of course, the capacity or displacement of the pump will vary in accordance with the tilt of the ring assembly 38 and will be zero when the ring assembly is perpendicular to the drive shaft.

Referring now to the feature of automatic variation in the capacity of the pump, the end of the drive shaft 36 which extends through the head 26 is hollow and has slidably fitted thereto a rod 52 and through which rod the pin 49 extends whereby reciprocation of said rod will correspondingly reciprocate the above-described member 47. Adjacent the outer end of said head 26 and reciprocable within the actuator housing 27 is a piston 53 and a ball 54 in the hollow end of the drive shaft is engaged between the end of said rod 52 and said piston 53.

Formed in the actuator housing 27 is a fluid chamber 56 in which a spring actuated plunger 57 is reciprocable to maintain a uniform pressure on the fluid in such chamber and thereby through the body of fluid acting on the piston 53 tend to urge the latter toward the right as viewed in Fig. 2 and through the ball 54, rod 52, pin 49, member 47, and link 48 tend to tilt the ring assembly 38 to a position to increase the capacity of the pump in opposition to the resistance to such tilting afforded by the fluid under pressure discharged from the pump acting on the ends of the pistons 30. The spring 58 for actuating the plunger bears against said plunger 57 and against a closure cap 59 threaded into the actuator housing. Said housing 27 is formed with a pair of ports 60 and 61 providing an inlet and discharge for fluid under pressure into and from such chamber 56.

As previously indicated, one function of the spring actuated plunger 57 is to smooth out any fluctuations in the fluid under pressure in the chamber whereby to maintain a more constant pressure acting upon the piston 53.

As apparent, a decrease of the fluid under pressure in the chamber 56 will permit the pressure acting on the ends of the pistons 30 to shift the ring assembly 38 to or toward a non-tilted position, thereby reducing the displacement of the pump to a desired value or to zero.

The ports 60 and 61 in the actuator housing 27 may optionally be connected into the discharge lines of the pump or to a separate source of fluid under pressure whereby in such latter instance remote control of the variation in the capacity of the pump may be conveniently effected.

A modification of the present invention as illustrated in Fig. 8 comprises pistons 65 each of which is formed with a peripheral groove 66 therearound in its intermediate section 67. In this case the outer ring 68 of the tilttable ring assembly may, if desired, be formed with a continuous ring portion 69 tiltably fitting within such peripheral groove. Moreover, the intermediate section 67 may be of circular cross-section, in which case the grooves 70 in the intermediate casing part 71 are not required for the purpose of non-rotatably supporting the pistons

as in Fig. 2 but may be provided for the purpose of preventing bending of the pistons and thereby reducing stresses at the ends of the pistons.

A still further modification of the present invention as illustrated in Fig. 7 comprises a sleeve 75 corresponding with the rod 52 in Fig. 2, said sleeve containing a spring 76 and spring guide 78 therein, a screw 79 adjustable in the end plate 77 on head 80 which is of construction similar to the head 26 previously described, and a ball 81 interposed between the end of said screw 79 and said guide 78. As apparent, adjustment of the screw 79 will effect corresponding adjustment of the tilt of the ring assembly through axial movement of the pin 82 which extends transversely through said sleeve and the axially elongated slot 83 in the drive shaft 84 and is connected to the member 47. Here again, as in the form of the invention illustrated in Figs. 1-6, the tilttable ring assembly is yieldably held by spring 76 in a desired adjusted tilted position in accordance with the setting of the screw 79.

The above-described embodiments of this invention are, of course, to be regarded as merely typical and, as obvious, the structure illustrated in Figs. 1-6 may incorporate either or both of the modifications illustrated in Figs. 7 and 8.

Other modes of applying the principle of the invention may be employed, change being made as regards the details described, provided the features stated in any of the following claims, or the equivalent of such, be employed.

I therefore particularly point out and distinctly claim as my invention:

1. A pump comprising a hollow casing formed with fluid inlet and discharge passages at opposite ends and at least two coaxial cylinder bores respectively communicating with such passages, a piston having its opposite ends reciprocable within such cylinder bores, check valves interposed between such cylinder bores and adjacent passages operative to open communication between an intake passage and cylinder bore during movement of said piston in one direction and to open communication between a cylinder bore and discharge passage during movement of said piston in an opposite direction, a drive shaft journaled in said casing, and a ring carried by said shaft for rotation therewith and engaged with an intermediate section of said piston, said casing being formed with a groove parallel to such bores in which groove the intermediate section of said piston is slidable.

2. A pump comprising a hollow casing formed with fluid inlet and discharge passages at opposite ends and at least two coaxial cylinder bores respectively communicating with such passages, a piston having its opposite ends reciprocable within such cylinder bores, check valves interposed between such cylinder bores and adjacent passages operative to open communication between an intake passage and cylinder bore during movement of said piston in one direction and to open communication between a cylinder bore and discharge passage during movement of said piston in an opposite direction, a drive shaft journaled in said casing, and a ring carried by said shaft for rotation therewith and engaged with an intermediate section of said piston, said casing being formed with a groove parallel to such bores and of cross-section complementary with that of the intermediate section of said piston, the intermediate section of said piston being of non-circular cross-section whereby to be non-rotatable in such groove, said piston being formed

with a recess, and said ring being formed with a projection extending into and tiltable within such recess.

3. A pump comprising a casing part of tubular form provided with a plurality of uniformly spaced, axially extending grooves in its inner surface, a cylinder block at each end of said casing part formed with cylinder bores axially therethrough in alignment with such grooves, a head adjacent each cylinder block formed with fluid inlet and discharge passages leading to the cylinder bores in the adjacent cylinder block, a plurality of pistons slide-guided in such grooves and having their opposite ends reciprocable within such cylinder bores, a drive shaft rotatably supported within said casing part and cylinder blocks and extending exteriorly through one of said heads, a tilted ring non-rotatable on said shaft and engaged with each of said pistons whereby to effect reciprocation of said pistons during rotation of said shaft and ring, and valve means between said heads and blocks for alternately opening and closing communication between such cylinder bores and such inlet and discharge passages during reciprocation of said pistons.

4. A pump comprising a casing part of tubular form provided with a plurality of uniformly spaced, axially extending grooves in its inner surface, a cylinder block at each end of said casing part formed with cylinder bores axially therethrough in alignment with such grooves, a head adjacent each cylinder block formed with fluid inlet and discharge passages leading to the cylinder bores in the adjacent cylinder block, a plurality of pistons slide-guided in such grooves and having their opposite ends reciprocable within such cylinder bores, a drive shaft rotatably supported within said casing part and cylinder blocks and extending exteriorly through one of said heads, a tilted ring non-rotatable on said shaft and engaged with each of said pistons whereby to effect reciprocation of said pistons during rotation of said shaft and ring, and valve means between said heads and blocks for alternately opening and closing communication between such cylinder bores and such inlet and discharge passages during reciprocation of said pistons, a pin transversely through said shaft and ring supporting the latter for tilting movement with respect to said shaft, mechanism for tilting said ring slidably axially on and non-rotatable with respect to said shaft, said mechanism being connected to said ring at a point radially spaced from the axis of said pin whereby to effect adjustment of the tilt of said ring upon axial movement of said mechanism, and means for axially moving said mechanism on said shaft.

5. The structure according to claim 4 further characterized in that said last-named means comprises an actuator housing adjacent one of said heads formed with a chamber for fluid, a piston reciprocable in said housing and engageable with said tilting mechanism, and a spring actuated plunger in such chamber adapted to exert pressure on fluid in such chamber to actuate said piston.

6. A drive shaft assembly for pumps comprising a shaft, a ring non-rotatably but tiltably mounted on said shaft for tilting about an axis transverse to the longitudinal axis of said shaft, a first member for tilting said ring non-rotatably connected to said ring and axially slidable on said shaft operative to tilt said ring responsive to relative axial movement of said member and

shaft, said shaft being hollow at one end with a slot transversely through the wall thereof, and a second member axially reciproable within said shaft and connected through such slot to said first member to axially shift the latter.

7. A pump comprising a hollow casing formed with fluid inlet and discharge passages at opposite ends and at least two coaxial cylinder bores respectively communicating with such passages, a piston having its opposite ends reciproable within such cylinder bores, check valves interposed between such cylinder bores and adjacent passages operative to open communication between an intake passage and cylinder bore during movement of said piston in one direction and to open communication between a cylinder bore and discharge passage during movement of said piston in an opposite direction, a drive shaft journaled in said casing, and a ring carried by said shaft for rotation therewith and engaged with an intermediate section of said piston, said casing being formed with a groove of cross-section complementary with that of the intermediate section of said piston, in which the intermediate section of said piston is slidably fitted, said piston being formed with a recess, and said ring being formed with a projection extending into and tiltable within such recess, such projection being in the general form of a gear tooth having a rolling action in such recess.

8. A pump comprising a hollow casing formed with fluid inlet and discharge passages at opposite ends and at least two coaxial cylinder bores respectively communicating with such passages, a piston having its opposite ends reciproable within such cylinder bores, check valves interposed between such cylinder bores and adjacent passages operative to open communication between an intake passage and cylinder bore during movement of said piston in one direction and to open communication between a cylinder bore and discharge passage during movement of said piston in an opposite direction, a drive shaft journaled in said casing, and a ring carried by said shaft for rotation therewith and engaged with an intermediate section of said piston, said casing being formed with a groove of cross-sec-

tion complementary with that of the intermediate section of said piston, in which the intermediate section of said piston is slidably fitted, said piston being formed with a recess, and said ring comprising an inner member carried by said shaft for rotation therewith and an outer member rotatable on said inner member and being formed with a projection extending into and tiltable within such recess, such projection being in the general form of a gear tooth having a rolling action in such recess.

9. A pump comprising a casing formed with fluid inlet and discharge passages at opposite ends and at least two coaxial cylinder bores respectively communicating with such passages, a piston having its opposite ends reciproable within such cylinder bores, a drive shaft rotatably supported in said casing, a member carried by said shaft for rotation therewith and for tilting movement thereon, mechanism for adjustably tilting said member on said shaft, said piston being formed with a cut-away portion, said member being formed with a projection extending into and tiltable within such cut-away portion, and such projection being in the general form of a gear tooth having a rolling action in such cut-away portion, and valve means within said casing to alternately open and close communication between such cylinder bores and passages during rotation of said shaft and subsequent reciprocation of said piston in such cylinder bores.
